UNITED STATES PATENT OFFICE.

JOHN A. PLUMLEY, OF BALTIMORE, MARYLAND.

DESIGN FOR A FRUIT-PICKER.

SPECIFICATION forming part of Design No. 27,209, dated June 15, 1897.

Application filed April 5, 1897. Serial No. 630,864. Term of patent 14 years.

To all whom it may concern:

Be it known that I, JOHN A. PLUMLEY, a citizen of the United States, residing at Baltimore, in the State of Maryland, have invented 5 a certain new and useful Design for Fruit-Pickers; and I do hereby declare the following to be a full, clear, and exact description of the invention, such as will enable others skilled in the art to which it appertains to 10 make and use the same.

This invention relates to a certain new and original design for fruit pickers or gatherers.

The object of the invention is to provide a 15 new, attractive, and useful shape or design of fruit-picker having peculiarity located and arranged picking-fingers, so that a shape of exceedingly artistic and attractive nature is produced.

The invention consists in the new and attractive shape or design of fruit-picker, substantially as shown in the drawings, and more 20 particularly pointed out and described hereinafter.

Referring to the accompanying drawings, 25 Figure 1 is a perspective view of the new shape of fruit-picker. Fig. 2 is an edge view thereof.

The characteristics of my new shape or de-

sign of fruit-picker reside in the metal ring A, having the curved tapered fingers B, extending upwardly from one portion thereof. 30

The fruit-picker is formed of a single length of wire or a metal rod with the two ends brought together to form the arm C, while the remainder of the wire is bent to form the ring A, having the upwardly-extending tapered fingers B bent from the wire and arranged at a point diametrically opposite the arm C, which extends outwardly and downwardly at an angle from the ring. The spaces between the fingers, three fingers being 35 shown, taper downwardly, while the upper ends of the fingers are curved or bent over the open space within the ring.

Having thus fully described my invention, what I claim, and desire to cover by Letters 45 Patent of the United States, is—

The design for a fruit-picker, substantially as described and shown.

In testimony whereof I affix my signature in presence of two witnesses.

JOHN A. PLUMLEY.

Witnesses:

WM. B. SHRYOCK,
CHAS. G. BALDWIN.
